(57) **CLAIM**

The ornamental design for a coupler seal, as shown and described.

DESCRIPTION

FIG. 1 is a top perspective view of a coupler seal; FIG. 2 is a bottom perspective view of the coupler seal of FIG. 1; FIG. 3 is a right side elevational view of the coupler seal of FIG. 1; FIG. 4 is a left side elevational view of the coupler seal of FIG. 1; FIG. 5 is a front elevational view of the coupler seal of FIG. 1; FIG. 6 is a rear elevational view of the coupler seal of FIG. 1; FIG. 7 is a bottom plan view of the coupler seal of FIG. 1; and, FIG. 8 is a top plan view of the coupler seal of FIG. 1. The broken lines in FIGS. 1-2 and 7-8 represent structure and boundaries that are not part of the claimed design, but rather show the environment in which the design is associated.

1 Claim, 8 Drawing Sheets
